ELECTRIC DRY SHAVER

George G. Going, Stamford, Conn., assignor, by
mesne assignments, to Remington Rand Inc.,
Buffalo, N. Y., a corporation of Delaware

Application June 21, 1938, Serial No. 214,896

5 Claims. (Cl. 30—43)

This invention relates to improvements in electric razors, and particularly to a novel combination of shearing members therein affording means for adequately cutting both long and short hairs.

Razors which are adapted to cut both long and short hair are well known in the art, but it has been the practice to provide one set of shearing members for both operations. It is obvious that in shaving it is necessary to have a thin outer shear plate or cutter which will permit the hair to be cut close to the skin, whereas in cutting long hair such a thin outer shear plate is not necessary. In cutting long hair it is necessary to provide some form of combing medium having teeth by which the hair may be aligned with the shearing members. It has also been found that an inner cutter which is satisfactory for shaving is often unsatisfactory for cutting long hair, and vice versa.

It is, therefore, the principal object of this invention to provide a shearing head for razors of this type, having separate inner cutters cooperating with a specially designed stationary shear plate for cutting long and short hair, respectively.

Another object is to provide separate and distinct cutters in the shearing head for cutting long and short hairs respectively.

A still further object is to provide an auxiliary cutting member which is adapted to cut long hair, and which is driven from the same source as the cutter for short hair.

A more clear conception of the construction, operation, and further objects of the invention may be had from the following detail description when taken in conjunction with the accompanying drawings, in which—

Fig. 1 is a side elevational view of an embodiment of the invention with parts broken away to show the operating mechanism;

Fig. 2 is a plan view of Fig. 1 with parts broken away to show the inner cutter;

Fig. 3 is a plan view of the auxiliary inner cutter for cutting long hair;

Fig. 4 is a cross section taken substantially along line 4—4 of Fig. 1;

Fig. 5 is a cross sectional view of Fig. 1 taken substantially along line 5—5 thereof;

Fig. 6 is a detail transverse section showing the driving connection for the auxiliary inner cutter;

Fig. 7 is a plan view of the inner cutter for cutting short hair;

Fig. 8 is a front elevational view of the cutter shown in Fig. 7.

Like characters of references refer to like parts in all the drawings.

The new shearing head and its associated driving mechanism is adapted to be incorporated in any well known type of electric razor in which the inner cutter is reciprocated. A razor of this type comprises a motor casing 10 which constitutes the handle of the razor, and in which may be mounted any suitable type of motor either of the vibrator or rotating type.

The shearing head 11 is located in a longitudinal slot in the top of the casing 10 and secured thereto by a set screw 12, as shown in Fig. 4. The shearing head comprises a fixed outer shear plate or shear member 14 which is substantially rectangular in shape, having the upper surface ground to an arcuate shape. One side of shear member or plate 14 is formed with a flange 15 having slots cut therein to form cutter bars and comb teeth 16. The upper surface of the shear plate is provided with perforations 17 forming shearing edges.

The inner cutter 28 (Figs. 7 and 8) is cylindrical in shape, having an eccentric bore, and cut in the thinner portion of the cutter is a plurality of slots located at an angle to the longitudinal axis of the bore. These slots extend into the bore and form cutter bars 21. A slot 22 is formed in the inner cutter diametrically opposite to the bars 21, which is adapted to be engaged by an arm 23 pivotally mounted on stud 24, and reciprocated by the motor. The stud 24 is screwed into a bushing 27 secured in the casing 10 by any well known means.

Located in the casing is a plate 25 in which is positioned a pair of spring pressed pins 26 which cooperate with the underside of the inner cutter, thereby insuring close contact between the cutter bars 21, and the perforations 17 in the outer cutter.

The perforated portion of the shear plate when moved over the face will pick up the hair which enters the perforations 17 where it is cut by the action of the bars 21 cooperating with the edges 45 of the perforations. Since the metal of the shear plate is very thin, the hair will be cut close to the skin.

The bars 16 in the flange 15 (Fig. 4) referred to above, are provided for cutting long hair, and cooperating therewith is an auxiliary cutter 30. The cutter is substantially channel shaped, and is positioned with the web portion against the side of the shear plate and the shorter of its flanges engaged with the underside of flange 15. The 55 shorter flange is slotted to form cutter bars 31.

which are adapted to cooperate with bars 16 for cutting long hair. The auxiliary cutter 30 may be reciprocated by the inner cutter 20, or by a number of independent means, several types of which will be described hereinafter. The under surface of flange 16 and the upper face of cutter 30 are formed at an angle of approximately 15° to the horizontal. This angular contact prevents the blade 30 from slipping out of position while running.

In Figs. 1, 2, 4, and 5 the cutter 30 is disclosed as being driven by the inner cutter. The shear plate 14 has a slot 32 cut therein, through which extends a pin 33 riveted in the web of the cutter 30. The pin 33 is adapted to cooperate with an aperture 34 in the inner cutter 20 in such a manner that any lateral movement of the inner cutter will be transmitted to the auxiliary cutter 30.

Positioned in the plate 25 is a spring pressed pin 35, which has a reduced head adapted to enter a hole in the lower flange of the auxiliary cutter. The pin 35 forces the cutter upward against the under surface of the flange 15, thereby insuring the close cooperation of cutting members 16 and 31.

When the cutter bars 16 are moved across skin containing long hairs, the hair is combed in between the bars and there cut by the action of cutter bars 31 and 16.

The angular relation of the under faces of cutter projections 15 to the side wall of the shaver head is inclined at an acute angle to provide a retaining groove for the auxiliary cutter. With the cooperation obtained from the resilient means engaging the auxiliary cutter, it is held in proper operative position for cutting cooperation with projections 15 in cutting long hair without requiring the provision of other guide means or retaining means to maintain the auxiliary cutter in operative relation with projections 15.

It will also be clear that in using the shaver the surface of the shaver head, formed with projections 15 and perforations 17, can be applied to the face or other surface to be shaved, so that when the shaver is moved in a direction parallel to the plane of projections 15 and with the free ends of projections 15 leading in the direction of movement of the shaver over the face or other surface, long hairs will be cut first between projections 15 and short hairs will be subsequently and simultaneously cut in perforations 17. When it is desired to shave only short hair, the shaver may be used in such a way that only the portion provided with perforations 17 is engaged with the surface to be shaved. The side portion of the shaver under projections 15 is entirely open for a substantial distance to allow the projections to be freely and easily engaged with long hair. This enables the shaver to be used for trimming mustaches, sideburns, the back of the neck, etc., with the side projections 15.

What I claim as new, and desire to secure by Letters Patent is:

1. A shaver, comprising a shear member having a base and an outwardly directed curved shaving section said shaving section having outer and inner partially cylindrical surfaces providing said section with a substantially thin cross section attached at both sides to the remainder of said shear member including said base, said section having a plurality of perforations extending between said inner and outer surfaces, cutting edges being formed on said section

around the inner edges of said perforations, an inner cutter mounted to have cutting edges formed thereon engage the inner surface of said shaving section for cutting cooperation with the cutting edges thereof in the movement of said inner cutter over the inner surface of said shaving section, a plurality of projections extending laterally in spaced parallel relation from one side of said shear member, having the opposite ends free and forming open ended slots therebetween, said projections lying in the same plane and having coplanar faces on the side facing said base extending in inclined relation to the plane of the adjacent side wall of said shear member and toward said base to form a retaining groove with said side wall, and an auxiliary cutter guided in said groove by said projections and side wall having a pair of adjacent sides slidably engaged in said retaining groove in sliding contact with said coplanar faces and said side wall and having the portion engaging said cutter projections formed to provide a plurality of spaced parallel cutter bars formed for cutting cooperation with said projections in the reciprocation of said auxiliary cutter and simultaneous cooperative shaving operation with said shaving section and inner cutter.

2. A shaver, comprising a shear member having a base and a curved shaving section of substantially thin cross section attached at opposite sides to the sides of said base, said shaving section having a plurality of perforations to provide a plurality of cutting edges on said section about the margins of said perforations, an inner cutter mounted in said shear member and having cutting edges cooperating with the cutting edges of said shaving section in the movement of said inner cutter over the inner surface of said shear member, a plurality of spaced parallel projections mounted at one end on one side of said shear member at one end of said shaving section, said projections extending laterally from the side of said shear member and providing open ended slots therebetween with the side edges of said projections forming cutting edges extending laterally from said shear member, and an auxiliary cutter having a plurality of spaced parallel projections formed to provide cutting edges on the sides thereof extending laterally from the side of said shear member, having open ended slots therebetween and having cutting cooperation with said first-mentioned projections in relative movement thereof, whereby movement of said shaver over the surface to be shaved with the free ends of said projections in the lead and with the direction of movement in line with said projections, said projections will cooperate to receive and cut long hair therebetween and said shaving section will have the inner cutter cooperate simultaneously with the cutting edges about said perforations therein for cutting short hair.

3. A shaver comprising a shear member having a curved shaving section of substantially thin cross section joined at opposite sides to the sides of the base of said member and formed with a plurality of perforations to provide a plurality of cutting edges on said section about the margins of said perforations, an inner cutter mounted to have cutting edges formed thereon engage the inner surface of said shaving section for cutting cooperation with the cutting edges thereof in the movement of said inner cutter over the inner surface of said shaving section, a plurality of projections extending laterally in spaced parallel relation from one side of said

shear member and having one end of each of said projections secured thereto, one face of said projections lying in the same plane and arranged in acute angular relation to the side wall of said shear member adjacent said base and cooperating therewith to form a retaining groove, said projections having slots therebetween open at the free ends thereof, an auxiliary cutter formed to provide a pair of adjacent sides slidably engaging said projections and the adjacent side wall of said shear member respectively, said auxiliary cutter seating in said retaining groove and having the portion engaging said projections formed with a plurality of spaced parallel teeth having cutting cooperation with said projections in the movement of said auxiliary cutter relative to said projections, resilient means normally operating to project said auxiliary cutter toward said projections for cooperation therewith in retaining said auxiliary cutter in said retaining groove and guiding the same in its cutting operation, and means for actuating said inner and auxiliary cutters simultaneously.

4. A shaver comprising a shear member having a curved shaving section of substantially thin cross section joined at opposite sides to the sides of the base of said member and formed with a plurality of perforations to provide a plurality of cutting edges on said section about the margin of said perforations, an inner cutter mounted to have cutting edges formed thereon engage the inner surface of said shaving section for cutting cooperation with the cutting edges thereof in the movement of said inner cutter over the inner surface of said shaving section, a plurality of projections extending laterally in spaced parallel relation from one side of said shear member having the opposite ends free and forming open ended slots therebetween, said projections lying in the same plane and the plane of said projections extending in inclined relation toward said base to the plane of the adjacent side wall of said shear member to form a retaining groove, an auxiliary cutter formed of an angle member having one portion slidably engaging the side wall of said shear member and the other portion extending in inclined acute angular relation to the free edge of the first portion and slidably

engaging said projections in said retaining groove, said last-mentioned portion being formed to provide a plurality of spaced parallel projections parallel to said first-mentioned projections formed for cutting cooperation with said first-mentioned projections in the reciprocation of said angle member in said retaining groove, resilient means for retaining said angle member in said retaining groove, said resilient means and first-mentioned projections cooperating to normally retain said auxiliary cutter against detachment from said projections and shear member, and means for actuating said inner and auxiliary cutters simultaneously.

5. A shaver comprising a shear member having a base and a curved shaving section extending outwardly from said base and formed with a plurality of perforations to provide a plurality of cutting edges on said section about the margins of said perforations, an inner cutter mounted to have cutting edges formed thereon engage the inner surface of said shaving section for cutting cooperation with the cutting edges thereof in the movement of said inner cutter over the inner surface of said shaving section, a plurality of projections extending laterally in spaced parallel relation from one side of said shear member, having the opposite ends free and forming open ended slots therebetween, said projections lying in the same plane and extending toward said base in inclined relation to the plane of the adjacent side wall of said shear member to form a retaining groove, an auxiliary cutter guided in said groove by said projections and having the portion engaging said projections formed to provide a plurality of spaced parallel cutter bars formed for cutting cooperation with said projections in the reciprocation of said auxiliary cutter, and means for actuating said inner and auxiliary cutters simultaneously having a lever engaging said auxiliary cutter operable to transmit reciprocating motion thereto to produce the cutting operation of said auxiliary cutter and resilient means mounted thereon and engaging said auxiliary cutter for normally retaining said auxiliary cutter in operative cutting relation in said retaining groove against detachment.

GEORGE G. GOING.
